UNITED STATES PATENT OFFICE.

JESSE E. SHULL, FRANKLIN M. SHULL, AND JOHN W. SHULL, OF ALPENA, SOUTH DAKOTA.

JACK FOR CONTAINERS.

1,295,377.

Specification of Letters Patent. Patented Feb. 25, 1919.

Application filed October 3, 1917. Serial No. 194,584.

To all whom it may concern:

Be it known that we, JESSE E. SHULL, FRANKLIN M. SHULL, and JOHN W. SHULL, citizens of the United States, residing at 5 Alpena, in the county of Jerauld and State of South Dakota, have invented certain new and useful Improvements in Jacks for Containers, of which the following is a specification, reference being had to the accompanying drawings.

This invention relates to an improved jack for barrels, tanks, and like containers, and has for its primary object to provide a simple and easily operated device for moving a barrel filled with liquid from a vertical to a horizontal position in order to dispense the contents thereof, or from a horizontal to a vertical position when the barrel is to be refilled.

It is another and more particular object of the invention to provide a device for the above purpose, embodying a suitably constructed base, supporting means for the barrel or container movably mounted upon the base, means for pivotally or tiltably mounting the container upon the supporting means, and manually operable means for actuating the supporting means, whereby the barrel or container may be disposed in either a vertical or horizontal position with respect to the base.

It is a further object of the invention to devise a movable supporting means for the container and an operating means therefor, the several parts of which are so correlated that a very rigid and substantial supporting structure will be provided to sustain the container in a horizontal position above the base and prevent its accidental or unintentional movement with respect thereto.

The invention likewise has for one of its detail objects to provide in addition to a hand operated lever for the container support, foot operating means connected to one side of the container, whereby the container when in a vertical position, may be initially lifted from the base to facilitate the operation of the supporting means in the movement of the container to a horizontal position.

It is also a further general object of our invention to provide a barrel or container jack as above characterized, which is exceedingly strong and durable in its construction, highly convenient and serviceable in practical use, and likewise capable of manufacture at relatively small cost.

With the above and other objects in view, our invention consists in the novel features of construction, combination, and arrangement of parts to be hereinafter more fully described, claimed, and illustrated in the accompanying drawings, in which,

Figure 1 is a side elevation showing the barrel or container in full lines in its vertical position and in dotted lines in a horizontal position;

Fig. 2 is a similar view to Fig. 1, looking at the opposite side of the container;

Fig. 3 is a horizontal sectional view taken on the line 3—3 of Fig. 1, showing the relative positions of the parts when the container is in a horizontal position;

Fig. 4 is a horizontal sectional view taken on the line 4—4 of Fig. 1; and

Figs. 5 and 6 are detail perspective views of the respective gudgeon plates or brackets.

Referring in detail to the drawings, 5 designates the spaced, parallel sills or beams of a base structure which are rigidly connected to each other at their opposite ends by the transverse bars 6 and 7 respectively. Between the connecting bar 6 at the outer longitudinal edge thereof and the ends of the bars 5, the bearing plates indicated at 8 85 are rigidly secured by means of vertical bolts 9 extending through the bars 5 and 6. Each of these plates is provided in its central portion with a bearing cuff or sleeve in which a hollow pipe or rod 10 is rotatably 90 mounted. The opposite ends of this pipe are exteriorly threaded to receive the elbow coupling members 11. In these elbows, the lower ends of the tubular standards 12 have threaded engagement.

Bearing members 13, similar to the members 8, are likewise secured by bolts 14 between the inner longitudinal edge of the other end bar 7 of the base and the bars 5, and in these bearing members a solid rod or 100

- shaft 15 is likewise rotatably mounted. This rod 15 is provided with an angular arm 16 on each of its ends, said arms extending upwardly above the base bars 5.
- 5 B designates the barrel, tank, or other container which, in the illustrated embodiment of our invention, is of cylindrical form and may be of any desired capacity. This container is provided on one end with a 10 faucet or valve *b* whereby its contents may be drawn. Upon the wall of the container B midway between its ends and at diametrically opposite points, the cruciform gudgeon plates designated 17 and 18 respectively, are arranged. The arms 19 of these plates projecting longitudinally of the tank or container, bear against the wall thereof and prevent tilting or angular movement of the plates with respect to the container wall.
- 15 Each of these plates is centrally provided with a cylindrical bearing stud or gudgeon 20 and 21 respectively. To one of the other arms 22 of the gudgeon plate 17, one end of a metal band section 23 is securely 20 riveted, and to the other end of this band section, a short length of link chain 24 is connected. The other arm 25 of the gudgeon plate 17 terminates in a hook 26 adapted for engagement through an opening in 25 one end of the relatively long band section 27. To the other end of this latter band section, an eye 28 is secured for a purpose to be presently stated. A third band section 29 is riveted at one of its ends to the 30 circumferentially extending arm 30 and the gudgeon plate 18, and the other end of said band section is angularly bent, as at 31, and apertured to receive the threaded bolt 32 upon one end of which the nut 33 is 35 engaged. The other end of this bolt terminates in a hook 34 which is adapted for engagement in one of the links of the chain 24 connected to the band section 23. The other circumferentially extending arm 35 40 of the gudgeon plate 18 also terminates in a hook 36 and is adapted to be engaged by one of the links of a chain 37. A threaded bolt 38 is engaged through the eye 28 on the band section 27 and is provided with a terminal hook 39 for engagement with one of the links of the chain 37. A clamping nut 40 is threaded upon the bolt 38 to co-act with the eye 28. Thus, it will be seen that this sectional clamping band can be readily 45 adjusted and tightly clamped around the tank or container to securely retain the gudgeon plates 17 and 18 in their applied positions and hold the same against relative shifting movement.
- 50 The upper ends of the standards 12 are flattened and provided with openings to receive the respective gudgeons 20 and 21. Rods 41 are also loosely engaged at one of their ends upon the respective gudgeons and

have their other ends bifurcated to receive 65 the flattened terminals of the crank arms 16 on the rod 15, to which the rods 41 are pivotally connected by the bolts indicated at 42. Cotter pins or other retaining elements are engaged with the outer ends of the gudgeons to retain the rods 41 and the standards 12 in connection therewith. To one of the crank arms 16, the angular end of an operating lever 44 is bolted, welded, or otherwise securely fixed.

70 In addition to the hand lever 44, we also provide a foot-operated lever 45 fulcrumed in spaced relation to one of its ends, as at 46, between the upper ends of vertically disposed, converging, bracket members 47 80 which are fixed to one of the base bars 5. This end of the lever 45 is pivotally connected to one end of a metal bar 48, the other end of which is slotted, as at 49, and engaged upon the gudgeon 21 between the plate 18 and the end of the standard 12. To this standard 12, intermediate of its ends, an angular bracket plate 50 is secured, and between the offset end of said plate and the standard, the hand-operated lever 44 is 90 adapted to engage to limit the movement of said lever when the barrel or container is disposed in a horizontal position as clearly shown in dotted lines in Fig. 1 of the drawings.

95 At the relatively opposite side of the container with respect to the operating levers, a metal bar 51 is loosely engaged at its other end upon the rod 15. The other or upper end of this bar is slotted, as at 52, for relative movement upon a pin or stud 53 fixed in a plate 54 secured upon the band section 27 adjacent to the gudgeon plate 17. It will be noted that the plate 54 has its medial portion angularly offset from the band section 27 and disposed in a plane substantially parallel with the base structure when the barrel or container is in a vertical position. The slot 52 in the bar 51 permits of a downward and forward tilting movement of the 100 barrel or container when the same is in a horizontal position, so that said container may be completely drained of its contents.

105 Parallel track rods 55 extend longitudinally upon the upper surfaces of the base bars 5 and have angular ends 56 extending through coinciding openings in said bars and the end bars 6 and 7 of the base. Suitable retaining nuts are engaged upon the threaded terminals of these rods. These 110 rods provide a metallic track upon which the barrel end will have free sliding movement in its adjustment to a vertical or horizontal position with respect to the base.

115 From the foregoing description, taken in connection with the accompanying drawings, the construction and several advantages of our invention will be manifest. When the

barrel or container is in vertical position as shown in dotted lines in Fig. 1 of the drawings, in which position it may be conveniently filled, in order to dispose the container in a horizontal position above the base, the operator first bears downwardly with his foot upon the upper end of lever 45, thus rocking this lever upon the supporting brackets 47 and forcing the bar 48 upwardly. This bar co-acting with the gudgeon 21 urges the barrel or container upwardly, thereby causing the standards 12 to swing toward a vertical position and to move the rods 41 into longitudinal alinement with the angular arms 16 on rod 15. When the barrel has thus been given its initial upward movement by the foot lever 45, the hand lever 44 swings over toward the operator who grasps said lever and pulls the same over and downwardly, thereby continuing the movement of rods 41 relative to the arms 16. As these rods move into alinement with the crank arms, the bar 51 exerts a downward pull upon the barrel or container, owing to the fact that the connection of this bar to the pin or stud 53 is spaced from the pivots or gudgeons on the barrel. Therefore, it is seen that the barrel will be tilted between the standards 12 and swung to a horizontal position. When the operating lever 44 is finally moved into engagement with the stop bracket 50, as shown in dotted lines in Fig. 1, the joints between rods 41 and the crank arms 16 are disposed slightly past or inwardly of the axial center of said rods so that the weight of the container and its contents tends to further urge the operating lever 44 downwardly upon the stop bracket 50. Thus, it will be seen that the supporting structure will be very substantially braced against the relative movement of its parts and the accidental return movement of the container to a vertical position upon the base structure. It is, of course, apparent that a mere reverse or upward movement of the lever 44 will break the joints between the rods 41 and the crank arms 16 in an outward direction so that the bar 51 will act to swing the barrel or container to a vertical position as it is lowered upon the base.

From the above, it will be seen that we have devised a very simple and durable barrel or container jack which may be operated with ease and facility and a minimum of exertion to dispose filled barrels or containers of large capacity into position to dispense the contents thereof or to enable the container to be refilled. The invention is particularly well designed for use in connection with tanks or containers for dispensing gasoline to retail purchasers. It is, however, apparent that our invention may also be advantageously employed for use in connection with containers for various other

commodities. It is also to be understood that while we have herein shown and described the preferred form, construction, and arrangement of the several elements employed, the device is nevertheless susceptible of considerable modification therein and we, therefore, reserve the privilege of adopting all such legitimate changes as may be fairly embodied within the spirit and scope of the invention as claimed.

Having thus fully described our invention, what we desire to claim and secure by Letters Patent is:—

1. A jack for containers and the like including relatively movable supporting members, means for swingingly mounting a container upon said supporting members, manually operable means to move the supporting members relative to each other, and additional means operable independently of the supporting members and concurrently therewith to swing the container to a predetermined position in the movement of said supporting members.

2. A jack for containers and the like including relatively movable supporting members, means for swingingly mounting a container upon said supporting members, manually operable means for moving the supporting members relative to each other, and additional means operatively connected to the container and movable with respect to the supporting members during the movement of the latter to swing the container to a predetermined position.

3. A jack for containers and the like including relatively movable supporting members, means for swingingly mounting a container upon said supporting members, an operating lever rigidly fixed to one of the supporting members to move said members relative to each other, and a bar pivotally mounted at one of its ends and operatively connected at its other end to the container to swing the container to a predetermined position in the relative movement of the supporting members.

4. A jack for containers and the like including relatively movable supporting members, means for swingingly mounting a container upon said supporting members, an operating lever rigidly fixed to one of the supporting members to move said members relative to each other, additional foot-operated means to initially move the container from one position thereof and start the relative movement of the supporting members, such movement being continued by the operation of said lever, and a bar pivotally mounted at one of its ends and operatively connected at its other end to the container to swing the container to a predetermined position in the relative movement of the supporting members.

5. A jack for containers and the like including a base, supporting members mounted for relative rocking movement upon said base, means for mounting a container for 5 swinging movement upon the supporting members, said container when in a vertical position resting upon the base, manually operable means to rock said supporting members and elevate the container above the 10 base, and additional means operatively connected to the container to swing the same to a horizontal position above the base in the relative rocking movement of the supporting members.
- 15 6. A jack for containers and the like including a base, supporting members mounted on the base for relative rocking movement, means for pivotally mounting a container directly upon one of said supporting 20 members, relatively movable connection between said means and the other of the supporting members, manually operable means directly connected to one of the supporting members to rock said members and elevate 25 the container above the base, and additional means movable relative to the supporting members and operatively connected to the container to swing the container to a predetermined position with respect to the base.
- 30 7. A jack for containers and the like including a base, supporting members mounted on the base for relative rocking movement, means for pivotally mounting a container directly upon one of said supporting 35 members, relatively movable connections between said means and the other of the supporting members, manually operable means directly connected to one of the supporting members to rock said members and elevate 40 the container above the base, and additional means movable relative to the supporting members and operatively connected to the container to swing the container to a predetermined position with respect to the base,
- 45 8. A jack for containers and the like including a base, supporting members mounted for relative rocking movement upon one of the supporting members, relatively movable connections between said means and the other supporting member, the container when in a vertical position resting upon said base, foot operated means for initially lifting the container from the base, a hand lever directly connected to one of said supporting members to continue the rocking movement 50 of said members relative to each other, and a relatively movable bar pivoted at one end and operatively connected to the container at its other end to swing said container to a

horizontal position with respect to the base in the continued rocking movement of the 55 supporting members.

9. A jack for containers and the like including a base, supporting members mounted for relative rocking movement upon the base, means for pivotally mounting the container directly upon one of the supporting members, relatively movable connections between said means and the other supporting member, the container when in a vertical position resting upon said base, a foot-operated lever mounted on the base, a member pivotally connected at one end to said lever and operatively connected at its other end to the container, said member in the operation of the foot lever imparting an initial lifting movement to the container, a hand lever directly connected to one of the supporting members subsequently operable to continue the rocking movement of said members, and means constructed and operating to swing 80 the container to a horizontal position with respect to the base in such relative movement of the supporting members.

10. A jack for containers and the like including a base, supporting members mounted for relative rocking movement upon the base, means for pivotally mounting the container directly upon one of the supporting members, relatively movable connections between said means and the other supporting member, the container when in a vertical position resting upon said base, a foot operated lever mounted on the base, a member pivotally connected at one end to said lever and operatively connected at its other end to the container, said member in the operation of the foot lever imparting an initial lifting movement to the container, a hand lever directly connected to one of the supporting members subsequently operable to 90 continue the rocking movement of said members, means constructed and operating to swing the container to a horizontal position with respect to the base in such relative movement of the supporting members, and 95 stop means on one of the supporting members preventing further movement of the hand lever in the latter position of the container and thereby preventing the casual reverse rocking movement of the supporting members.

11. A jack for containers and the like including means operable to bodily lift and support a container, and means automatically operable in such movement of the container to move the container to a predetermined angular position with respect to the supporting means, said supporting means including coacting parts movable into angular relation to retain the container in the 110 latter position.

12. A jack for containers and the like including manually operable means to bodily lift and support a container, and means operably connected to the container and actuated during the operation of said supporting means and independently thereof to move the container to a predetermined angular position with respect to the supporting means.

In testimony whereof we hereunto affix our signatures in the presence of two witnesses.
